[57] CLAIM

The ornamental design for a child's clothes rack and
growth measuring and registering unit, as shown and
described.

DESCRIPTION

FIG. 1 is a front elevational view of a child's growth
measuring and registering unit showing our new design;
FIG. 2 is a right side elevational view thereof, the left
side being a mirror image thereto;

FIG. 3 is a fragmentary front elevational view of the
simulative deer's head on an enlarged scale;

FIG. 4 is a rear elevational view of FIG. 3;

FIG. 5 is a right side elevational view of FIG. 3.
The broken line showings of FIGS. 1 and 2 are environ-
mental only and form no part of the claimed design.
